Primary Examiner — Jennifer L Rempfer*Assistant Examiner* — Elizabeth Anne Glassberg(74) *Attorney, Agent, or Firm* — Sanchelima & Associates, P.A.; Christian Sanchelima; Jesus Sanchelima(57) **CLAIM**

The ornamental design for an animal harness with video camera mount, as shown and described.

DESCRIPTION

FIG. 1 is an operational isometric view of an animal harness with video camera mount showing my new design; FIG. 2 is an isometric view of the animal harness with video camera mount; FIG. 3 is a front elevational view thereof; FIG. 4 is a rear elevational view thereof; FIG. 5 is a left side elevational view thereof; FIG. 6 is a right elevational view thereof; FIG. 7 is a top plan view thereof; and, FIG. 8 is a bottom plan view thereof showing my design. The broken lines in the drawings illustrate portions of the animal harness with video camera mount which form no part of the claimed design. The broken lines of the dog in FIG. 1 illustrate the claim in use and form no part of the claimed design.
